CAN OPENER

Robert E. McLean, Columbus, Ga., assignor to
John C. Hockery, Kansas City, Mo., as trustee

Application May 9, 1947, Serial No. 746,910

4 Claims. (Cl. 30—8.5)

1

This invention relates generally to the class of cutlery and is directed particularly to improvements in can openers of the rotary drive wheel type.

A principal object of the invention is to provide a can opener of the rotary drive wheel type, having a single operating handle by means of which clockwise rotation causes the device to puncture the end of the can and cut out the end of the can and subsequent counterclockwise rotation of such single operating handle releases the can from the device and wherein there is provided a novel thrust mechanism which is near the plane of the can driving wheel whereby to materially reduce operating friction and thereby provide easier and more efficient operation of the opener.

Another object of the invention is to provide a can opener of the rotary drive wheel type and employing a single operating handle by which the above described functions are attained, wherein a novel thrust mechanism is provided in the form of a pawl movable in a plane parallel with and adjacent to a side of a body plate with novel means for automatically interlocking such pawl with the means for rotating the drive wheel to effect relative shifting between the drive wheel and a cutter when the crank is turned in one direction and to effect automatic disengagement of the drive wheel rotating means after a predetermined operation of the handle in the said one direction whereby to permit continued rotation of the drive wheel for the performance of the can top cutting operation.

Another object of the invention is to provide a can opener of the rotary drive wheel type, with a simple, compact, inexpensive and efficient escapement mechanism for cooperation with the single operating handle to effect the thrust action required to puncture the end of the can and to release the can from the device upon completion of the operation of opening the can.

Other objects and advantages of the invention will become apparent as the description of the same proceeds and the invention will be best understood from a consideration of the following detailed description taken in connection with the accompanying drawings forming a part of the specification, with the understanding, however, that the invention is not to be understood as limited to the exact details of construction shown and described since obvious modifications will occur to a person skilled in the art.

In the drawings:

Figure 1 is a view in elevation of the right hand

side of the invention showing the escapement mechanism.

Figure 2 is a vertical section taken substantially on the line 2—2 of Figure 1.

Figure 3 is a view in elevation of the right hand side of the invention modified for mounting on a wall or other vertical surface and showing the escapement trigger mechanism in a more nearly horizontal position and in the position it assumes when the drive wheel and associate parts are in lowered position.

Referring now more particularly to the drawing the numeral 54 illustrates a body plate which is attached to a handle 55 by the rivets 56 and 57.

In the body plate 54 is formed the arcuate slot 58 in which is positioned the journal 59. This journal is mounted upon the shaft 60 which is of polygonal cross section and at the inner or left hand side of the body plate the shaft carries the spacer disk 61 while at the opposite or outer side there is secured on the shaft 60 the spacer disk 62 of comparatively large diameter as is clearly shown in Figures 1 and 2. This larger spacer disk 62 has anchored thereto the stud 63 and this stud extends through the lateral plane of the trigger link which is generally designated 64.

Upon the outer side of the large diameter disk 62, the shaft 60 carries the two spacer disks 65. These disks are interposed between the disk 62 and a portion of the operating handle, not shown, which is larger than the stem or shaft portion 60. Thus these elements through which the shaft portion 60 of the handle extends, are all secured to the shaft to rotate therewith.

The trigger link 64 is of substantial length and one end is pivotally mounted upon the rivet 56. Adjacent to the opposite or free end, the trigger link has a notch 66 formed in the under or bottom edge thereof for cooperation with the stud 63.

It will be understood, of course, that in connection with the invention there is employed a suitable cutter supporting head structure. A portion of this head structure is shown in Figure 2 and is generally designated 67, and carries a fixed cutter 67a in an offset parallel relation with the can driving wheel 67b.

Figure 3 illustrates a modified form of the invention adapted for mounting on a wall or other vertical surface and showing also the escapement trigger or trigger link positioned in a more nearly horizontal plane.

In this modification the body plate is generally designated 68 and is formed as an integral

part of the arm 69 which is designed for attachment to a vertical supporting surface.

The numerals 70 and 71 designate the two rivets which secure the body plate and the cutter support frame or head, not shown, together.

The head of the rivet 71, and also the head of the rivet 57 shown in Figures 1 and 2, extends outwardly through the lateral plane of the trigger link which is generally designated 72 and functions, like the head of rivet 57 as shown in Figure 2, as a stop for limiting the upward swinging of the trigger link.

The body plate 68 has the arcuate slot 73 therein corresponding to the slot 58 and positioned in this slot is a journal, not shown, corresponding to the journal 59 through which passes the shaft or rivet 75. As in the construction of Figures 1 and 2 the rivet 75 which functions as a shaft, carries the disk 76 of enlarged diameter together with other parts not shown, and upon the outer end of the shaft is secured an end of the crank 77. Between the crank 77 and the disk 76 are spacers 78 which function like the spacers 65.

The trigger link 72 is pivotally attached to the body plate by the pivot rivet 79 which passes through one end of the link as shown and between the link and the body plate is a spacer disk 80 which functions like the handle 55 to maintain the link at the proper position outwardly from the body plate to have engaged in the notch 81 formed in the lower edge and adjacent to the free end thereof, the stud 82 which is carried by the disk 76.

In the operation of the invention if the journal 59 is not in the extreme rearward end of the arcuate slot 58 the operating shaft 60 is rotated counterclockwise until it is in such position. The device is then placed with the end of the cutter blade 61a over the rim of the can and the operating handle is rotated clockwise to turn the shaft 60 in the same direction until the end is cut out of the can, upon completion of which the handle and shaft are rotated counterclockwise as far as possible to release the can from the device.

Gravity causes the link 64 to drop and the notch 66 to engage with the stud 63 as the shaft 60 is turned either clockwise or counterclockwise. Upon commencing the clockwise rotation of the shaft the stud 63 will be in approximately the position illustrated in Figure 3 and the lower edge of the trigger link will lie close to the spacers 65. As the operating shaft is rotated clockwise the journal 59 will be moved from the lower and rearward end of the slot 58 to approximately the position shown in Figure 1. When the stud 63 arrives at this position, the lower edge of the trigger link 64 engages the spacers 65 thereby preventing further clockwise swinging of the trigger link. As the operating shaft is operated further clockwise the stud 63 disengages from the notch 66 and upon continued clockwise turning of the shaft the stud 63 engages the under edge of the trigger link 64 and lifts the free end of the link upwardly and then allows it to seat again on the spacers 65.

Upon counterclockwise rotation of the shaft 60 the stud 63 engages with the notch 66 of the trigger link 64. Further counterclockwise rotation of the shaft moves the journal 59 to the rearward end of the slot 58. It will be seen that the stud 63 will engage the notch 66 upon either clockwise or counterclockwise rotation of the operating shaft regardless of the position of the

journal 59 at the time the stud 63 comes into alignment with the notch 66. Gravity of the trigger link 64 may be supplemented by a suitable spring, if desired.

It is believed that it will be readily apparent that the operation of the modified form shown in Figure 3 is the same as that of the construction shown in Figures 1 and 2.

I claim:

1. A can opener of the rotary drive wheel type, comprising a body having an arcuate slot, the slot having a low end and a high end, a cutter carried by the body above the high end of the slot, a journal mounted in the slot for rotation and for movement from one end of the slot to the other, a shaft extending through and secured to the journal to turn therewith, a can rim engaging driving wheel mounted upon the end of the shaft adjacent to the cutter, means upon the other end of the shaft for turning the same, a relatively long element supported upon the body above and to extend across the shaft, said element having a constant tendency to move down toward the shaft, a detent carried by the shaft below said element, and means forming a part of said element for receiving the detent upon clockwise or counterclockwise rotation of the shaft, the engagement of the detent in the receiving means therefor upon clockwise rotation of the shaft when the journal is in the low end of the slot, effecting the shifting of the journal to the high end of the slot and the freeing of the detent from the receiving means, and the said tendency of the element to move in the manner stated maintaining said element in a position for ready reengagement of the detent in the receiving means upon counterclockwise rotation of the shaft, during the operating period in which the journal is in the high end of the slot.

2. A rotary can opener of the character stated in claim 1, wherein said detent comprises a pin connected with the shaft to rotate therewith and extending parallel with the axis of the shaft and the said receiving means comprises a recess formed in said element into which said pin engages.

3. A can opener of the rotary drive wheel type comprising a body plate having an arcuate slot therein, the slot having a low end and a high end, a cutter mounted upon the body plate above the high end of the slot, a journal mounted in the slot for rotation and for movement therein from one end of the slot to the other, a shaft extending axially through the journal and secured thereto for rotation therewith, a can rim engaging driving wheel carried upon the end of the shaft adjacent to the cutter, a pair of spacer members mounted upon the shaft upon opposite sides of the journal, the spacer member remote from the driving wheel being in the form of a disk, a pin carried by the disk and extending away from the body plate in parallel relation with the shaft, means upon the opposite end of the shaft from the wheel for rotating the shaft, a relatively long member pivotally secured at one end to the body plate and extending across the shaft upon the side of said disk remote from the body plate, and a slot formed in the lower edge of said member and adapted to receive said pin upon clockwise rotation of the shaft when the journal is in the lower end of the arcuate slot to effect the shifting of the journal to the high end of the arcuate slot, the pin disengaging from said member when the journal reaches the high end of the arcuate slot to permit continued clockwise rotation of the

shaft, the said pin reengaging in the said slot formed in the lower edge of said member upon counterclockwise rotation of the shaft to effect the shifting of the journal to the low end of the arcuate slot.

4. An opener of the character described in claim 3, with a wheel rotatably mounted upon the body plate beneath the high end of the arcuate slot and upon the side of the body plate adjacent to the can rim engaging driving wheel, the said 10 rotatably mounted wheel having the adjacent spacer member in peripheral contact therewith, said adjacent spacer member being in the form of a disk and adapted to roll around the rotatably mounted wheel.
